Primary Examiner — Darlington Ly

(57) **CLAIM**

The ornamental design for a fuel tank for ships as shown and described.

DESCRIPTION

The patent or application file contains at least one drawing executed in color. Copies of this patent or patent application publication with color drawing(s) will be provided by the Office upon request and payment of the necessary fee.

1. Fuel tank for ships

1.1 is a front elevation view of a fuel tank for ships embodying our new design;

1.2 is a rear elevation view thereof;

1.3 is a left side elevation view thereof;

1.4 is a right side elevation view thereof;

1.5 is a top plan view thereof;

1.6 is a bottom plan view thereof; and

1.7 is a perspective view thereof.

The highlight colors in the drawings represent indications of surface contrast which form part of the claimed design.
